United States Patent Office.

HENRY D. MARTIN, OF YPSILANTI, MICHIGAN,

Letters Patent No. 60,764, dated January 1, 1867.

IMPROVED MACHINE FOR CUTTING FLY NETS.

The Schedule referred to in these Letters Patent and making part of the same.

TO ALL WHOM IT MAY CONCERN:

Be it known that I, HENRY D. MARTIN, of the city of Ypsilanti, county of Washtenaw, State of Michigan, have invented a new and useful Machine for Cutting Leather Horse-Fly Nets; and I do hereby declare that the following is a full, clear, and exact description of the construction and operation of the same, reference being had to the annexed drawing, making a part of this specification.

The nature of my invention consists in placing the leather upon the platform, "A," under grooved roller "B," which connects by cog-gearing cam roller "C C," driving bar knives "D D," up through platform "A," under grooved roller "B," and holds while the leather is passing over platform "A," and under grooved roller "B," dropping by springs alternately, as the cam roller, "C," in its revolution, permits the springs being attached to the bar knives, "D D."

What I claim as my invention, and desire to secure by Letters Patent, is—

The combination of the bar knives and springs "D D," and the cam roller "C C," substantially in the manner and for the purpose set forth in this specification, and shown in the drawings hereto annexed.

HENRY D. MARTIN.

Witnesses:

FRANK JOSLIN,
V. JOSLIN.
